UNITED STATES PATENT OFFICE.

RODERICK MACRAE, OF BALTIMORE, MARYLAND, AND CHARLES F. TAVENER, OF BOSTON, MASSACHUSETTS, ASSIGNEES OF ONE-THIRD TO PETER DEVENEY, OF BOSTON, MASSACHUSETTS.

ELECTRIC SWITCH.

SPECIFICATION forming part of Letters Patent No. 366,634, dated July 12, 1887.

Application filed October 27, 1886. Serial No. 217,360. (No model.)

To all whom it may concern:

Be it known that we, RODERICK MACRAE, of Baltimore, in the State of Maryland, and CHARLES F. TAVENER, of Boston, in the county 5 of Suffolk and State of Massachusetts, both citizens of the United States, have invented certain new and useful Improvements in Electric Switches, of which the following is a specification, reference being had therein to the accompanying drawings.

This invention relates to a switch for making, breaking, throwing in, and cutting out, and otherwise controlling electrical circuits, and although hereinafter described in its application to an electric light or lamp circuit, the invention is adapted for use in connection with any electric system or system of circuits.

The general object in view is to provide a switch in which sparks will not occur at the 15 contact-points at the instant of separation or connection of one circuit from or with another.

A subordinate object in view is the provision of mechanical devices for suddenly transferring the movable contact-plate from 20 one position to the other when connecting or cutting off a circuit.

Other objects and advantages of the invention will appear in the following description, and the novel features thereof will be particularly pointed out in the claims.

Referring to the drawings, Figure 1 is a plan of a switch constructed in accordance with our invention. Fig. 2 is a section on the line X-X of Fig. 1; and Fig. 3 is a section on the line 35 Y-Y of Fig. 1, relative positions being changed for the purpose of illustration.

Like letters of reference indicate like parts in all the figures of the drawings.

In the use of the well-known "spring-jack" 40 electric switch for strong currents sparks occur at the place of contact, and in time the switch becomes fused or otherwise fouled, so as to render its operation imperfect, whereby on inserting the "wedge" of that form of switch 45 one circuit is not well closed before the other is opened.

We employ, in connection with the wedge, a pivoted contact-plate, which is also curved or convex at its contact-face, so that sparks

cannot occur at the actual contact-point of the 50 plate; but if they do occur at all they must occur at the ends of the plate, so that the plate is never fused at the point where the contact finally rests; and, furthermore, by the action as hereinafter described the plate is self-cleaning at said point.

Upon any suitable base or support, A, there are arranged binding-posts 1, 4, 7, and 9. The posts 1 and 7 are formed as, or electrically connected with, brackets B B', respectively, 60 and upon the former is secured a flat spring, C, formed of electrically-conductive material, and having one end coiled about the bracket B for the simple purpose of giving the desired resiliency or extent and freedom of movement 65 to its opposite end, which is adapted for the pivotal attachment thereto of our contact-plate D. From the bracket B' there is extended a spring, E, toward and in line with the spring C.

The binding-post 4 is formed on or electrically connected with a contact-plate, F, arranged below the spring C and the shoe or contact-plate D. The post 9 is formed or electrically connected with a plate, G, arranged parallel with the springs C and E and provided with a standard, G', opposite the post 9, and with a guide-rod, G², extending from the standard to the post. The plate G may also be provided with a longitudinal guiding-flange, G³. Upon the rod G² is mounted the 70 yoke portion H' of one side, H², of a wedge, H, the opposite side, H³, of which is separated from the side H² by a block of insulating material, H⁴, and the three parts are bound together by screws H⁵, passing therethrough.

H⁶ represents the neck, which connects the yoke H' with the side H² of the wedge. Between the arms of the yoke H' and upon the rod G² are mounted the ends I' of a coiled spring, I, the said ends being curved about 90 the rod in the form of eyes, so as to retain said ends in connection with the rod and permit of free longitudinal movements thereof upon the rod. The yoke is adapted by the same construction to partake of the same 95 movements.

J represents a pivoted lever, the pivot J' of which is secured in the base or support A,

and the inner end of which is formed as a sector, J^2 , having lugs J^3 , adapted to embrace or partially embrace the arms of the spring I . The sector end of the lever is also provided 5 with transversely-wedge-shaped lugs J^4 , which project beneath the plate G .

The plate G is slotted longitudinally beneath the rod G^2 for the reception of latches K , supported in the slot by the pivots K' . Beneath 10 the outer ends of the latches are arranged springs K^2 for rendering the action of the latches more positive than if the action of gravity at their inner ends were solely relied upon.

15 Stops L are arranged upon the base or support A , to determine the extent of the movements of the sector end of the lever J .

The mechanical operation of our invention is as follows: Taking the parts as illustrated 20 in Fig. 1, the wedge H being between the contact-plate F and the shoe D , the latter resting horizontally upon the upper side, H^3 , of the wedge, the latter is quickly thrown from between the plates toward and beneath the 25 spring E by moving the free end of the lever J to the right. The first function of the lever is to compress the right arm of the spring toward the left arm, thereby storing power which shall suddenly throw the yoke 30 and the wedge connected therewith when the projection J^1 shall arrive at and pass beneath the free end of the latch K , which until this time has remained in contact with the right arm of the yoke to hold the left arm of the 35 spring against movement upon the rod while the right arm is being compressed. The advancement of the wedge-shaped lug J^4 during the latter part of the movement of the sector end of the lever lifts the free end of the latch, 40 which releases the yoke, and it is suddenly forced by the compressed spring to the opposite end of the rod upon which it is mounted, when the opposite latch, forced upwardly by its spring K^2 , assumes the position to retain 45 the yoke at that end of the rod until it is released by an opposite movement of the sector end of the lever and thrown by a compression of the spring during said operation of the lever.

By reference to Fig. 3 the advantage of the 50 shoe form given to the contact-plate D will be clearly understood. The position illustrated is that assumed by the shoe when passing from the plate F to the plate H^3 , and it will be seen that a substantially complete connection of 55 the shoe and plate H^3 at and along the central portion of the former occurs before the former has entirely left or is entirely separated from the plate F . Now, as sparks occur only at the point of making or breaking the circuit, it 60 will be seen that in this instance they must occur at the end of the shoe, and therefore its actual contact-point, which is substantially the central portion of its lower face, is preserved from injury by sparks, and at the same 65 time is rendered self-cleaning in its movements against and upon the insulating material and upper plate of the wedge.

Taking the electrical connections and circuits illustrated in Fig. 1, the latter being a "main circuit" connected with the posts 1 and 4 and a "lamp-circuit" connected with the posts 7 and 9, the electrical operation of our invention is as follows: There is a connection formed between the posts 1 and 7 electrically by means of the spring C , shoe D , and plate H^3 70 of the wedge, and the spring E , it being understood, as described, that the posts 1 and 7 are electrically connected with the spring by the brackets B B' . From the post 7 the current traverses the lamp-circuit to the post 80 9, and through the yoke and neck of the lower plate, H^2 , of the wedge to said lower plate, and from thence to the plate F and post 4, electrically connected therewith, at which point the main circuit is joined. By operating the 85 lever J , as described, the wedge is thrown from between the shoe and the plate F to and beneath the spring E , as shown by dotted lines in Fig. 1. The lamp-circuit is now cut out and the main circuit completed or closed by 90 the contact of the shoe D with the plate F .

M represents rubber or other suitable buffers mounted upon the rod G^2 to neutralize the mechanical shock or blow of the yoke against the post 9 and standard G' when thrown by 95 the spring.

Having described the construction and operation of our invention, what we claim is—

1. In an electrical switch, a curved switch-plate pivotally connected with a spring, in 100 combination with a spring-actuated sliding wedge, substantially as specified.

2. In an electrical switch, the combination of a wedge, a fixed contact-plate, and a centrally and yieldingly pivoted curved contact-plate, substantially as specified. 105

3. In an electrical switch, a wedge mounted for reciprocation upon a rod, spring-retaining latches, a spring, and a spring-compressing lever, substantially as specified. 110

4. The combination, with fixed and movable contact-plates, of a wedge connected by a yoke with and for reciprocation upon a rod, a spring having its arms arranged upon the rod within the yoke, and a spring-compressing lever, 115 substantially as specified.

5. In an electrical switch, the shoe D , having a convex contact-face, in combination with a sliding wedge, a spring, C , to which it is pivotally connected, and with a binding-post, 120 and a bracket electrically connected with the binding-post, substantially as specified.

6. The combination of the binding-posts 1 and 4, the plate F , the spring C , and the pivoted shoe D , with a spring-actuated wedge, 125 substantially as specified.

7. The combination of the binding-posts 1, 4, 7, and 9, the springs E and C , the pivoted shoe D , plate F , and the wedge H , with the plate G , and devices for reciprocating the 130 wedge upon the plate, substantially as specified.

8. The combination of the plate G , provided with the latches K and rod G^2 , of a

wedge-yoke and spring mounted upon the rod, and a lever having latch-lifting lugs and spring-operating lugs, substantially as specified.

5. The combination of a wedge and its yoke with the plate G, having the latches K and rod G², and with the spring I, mounted on the rod between the arms of the yoke, and a lever constructed and arranged to first com-
10 press the spring and afterward release a latch, substantially as specified.

10. The combination of the lever J, having the lugs J³ J⁴, with the plate G, having the

latches K, the rod G², and the wedge-yoke mounted thereon, and with the spring I, sub-
stantially as specified. 15

In testimony whereof we affix our signatures in presence of two witnesses.
